FLUORESCENT LIGHT FOR DISPLAY CABINETS

Herbert E. Grindstaff and Floye J. Bearden,
Los Angeles, Calif.

Application July 22, 1948, Serial No. 40,096

6 Claims. (Cl. 240—6)

1

This invention relates generally to lighting units for display cabinets, and finds one of its chief advantages in its adaptability for providing fluorescent lighting for refrigerated display cabinets.

In the lighting of such display cabinets, it has been difficult to use fluorescent light tubes because of the difficulties of installing and changing the tubes and also because the tubes are normally exposed to injury by people placing articles in and removing them from the cabinet.

It is one of the chief objects of our invention to provide a lighting unit which will overcome those difficulties and is so constructed and arranged that a fluorescent light tube may be installed or removed with a minimum of difficulty and yet, when installed in a cabinet, it provides maximum display illumination and is fully protected from damage.

Still further objects and advantages will appear hereinafter.

Without intending to limit the invention thereto, we show in the accompanying drawings a presently preferred embodiment illustrating one of the physical forms in which our invention may be carried out. In the drawings:

Fig. 1 is a sectional view of a display cabinet showing, in side elevation, our unit mounted therein;

Fig. 2 is a section taken on line 2—2 of Fig. 1;

Fig. 3 is a longitudinal sectional view of a portion of our unit, some parts being shown in elevation;

Fig. 4 is a section taken on line 4—4 of Fig. 3; and

Fig. 5 is a front elevation of a typical display cabinet in which our unit may be mounted.

Referring now to the drawings, the reference letter C generally denotes a display cabinet such as a refrigerated cabinet, and the numeral 5 generally denotes our lighting unit.

The cabinet has contiguous doorways 6, 7, 8, separated by T posts 9, there being doors 10, 11, 12, hingedly mounted in the respective doorways by hinge means 14. Each door frame 15 is conventionally lined with rubber sealing gasket material 16. The particular construction of the doors and doorways, however, does not form any part of our invention, since the invention is susceptible of being mounted in practically any cabinet.

A conventional power pack is housed within a casing 20 secured to the inside of the cabinet immediately above the dividing posts 9, being

2

connected to an electrical source through wires W. To the inside of the casing 20 there is secured a four-outlet socket member 21 providing sockets for reception of the four L-shaped prongs 22 of a twist lock connector 25.

We fix to the floor, at a point directly beneath the socket, a positioning plate or ferrule 27 having a peripheral flange 27a for the purpose to be described, the ferrule being secured as by screw 28. It will be observed that the ferrule 27 and the power pack are fixedly mounted in the cabinet.

Between the socket and the ferrule we mount, in the manner now to be described, armor tube 30 which, preferably, is of transparent plastic and has its outer half coated with a light reflective coating 31 (Fig. 4). The tube 30 has a bottom wall 32 but is open at its top end. The side wall of this tube at its top end portion is longitudinally slotted as shown at 34 for the purpose to be described.

Within the tube 30 we slidably mount a light unit consisting of end disks 35, 36, each carrying a socket 35a, 36a, for the reception of the ends 25 of a fluorescent light tube 37. The armor tube is shorter than the distance between socket 21 and the ferrule 27 so that when the lower end of the armor tube is positioned within the ferrule the upper end of the tube terminates short of the socket. A tube or cable 40, which is substantially rigid, is frictionally fitted at its ends in openings in the respective disks, being secured against escape therefrom by means of set screws 41, 42. The screw 42 projects at its outer end radially from the disk 35 and is adapted to slidably fit in the slot 34 so that the cable 40 is always positioned between the light tube 37 and the coated portion of the armor tube.

Two electrical wires W1 and W2 lead from socket 35a, through the disk 35 to the connector 25, and two wires W3, W4 lead from the lower socket 36a through the cable 40 and disk 35 to the connector 25. There is an excess length of wires W1—W4 between the upper disk 35 and the connector 25 for the purpose to be described.

As best seen in Figs. 1 and 3, the connector 25 is fixed to the flanged top end of a sleeve 45, as by screws 46, the sleeve slidably or telescopically fitting on the top end of the armor tube 30 and carrying a radial guide screw 48 which also serves as a terminal for a ground wire 49. The guide screw is positioned far enough from the lower end of the sleeve to permit the sleeve to be

axially moved on the armor tube until the screw is removed from the slot, to permit the sleeve to be rotated relative to the armor tube until the prongs 22 are engaged in or disengaged from the socket 21.

From the foregoing, it will be apparent that not only is the lighting tube fully protected by the armor tube, but it is extremely simple to quickly install and remove the lighting tube. To remove it, it is only necessary to rotate the armor tube and sleeve, with its carried connector, to the left, or counterclockwise, freeing the prongs from the socket. Being telescopically mounted on the armor tube, the sleeve may be moved downwardly on the armor tube to provide sufficient clearance between the prongs and the socket 21 to enable them to be disengaged and to enable the armor tube to be lifted from the position in figure 27 without disconnecting the wires W1—W4. The sleeve and the armor tube with its contents may be then moved outwardly from the cabinet and the armor tube to be withdrawn from its contained unit, after which a new lighting tube may be inserted between the sockets 35a, 36a. The armor tube is again installed and the entire unit may be placed back into the cabinet, after which the prongs of the connector are locked in the socket 25.

We claim:

1. A lighting unit for a display case or the like comprising: an electrical supply socket adapted to be fixedly mounted in said case in position spaced above the floor thereof, a transparent armor tube adapted to be disposed axially between said floor and socket, the tube being shorter than the distance from said floor to the socket, a sleeve telescopically mounted on the upper end of the tube, an electrical connector carried on the sleeve for locking engagement in said socket, a lighting element mounted in the armor tube, said element comprising a lower disk and an upper disk each shaped to slidably fit in the armor tube, a fluorescent light tube receiving socket carried by each disk, a substantially rigid tube secured to and holding the disks spaced apart longitudinally of the armor tube, electrical wires leading from the connector to the socket carried by the upper disk and wires leading through said substantially rigid tube to the socket carried by the lower disk; there being an excess length of said wires between the upper disk and the connector to allow the sleeve to be axially removed from the armor tube without disconnecting said wires.

2. A lighting unit for a display case or the like comprising an electrical supply socket adapted to be fixedly mounted in the case, a positioning plate adapted to be fixedly mounted in the case opposite the socket, a transparent armor tube adapted to be disposed axially between the socket and plate, the armor tube being shorter than the distance between said socket and plate, a sleeve telescopically mounted on the upper end of the tube, an electrical connector carried on the top end of the sleeve for locking engagement in said socket, an elongated electrical lighting tube mounted longitudinally in said armor tube, and wires leading from the connector to the lighting tube, there being an excess length of said wires between the connector and lighting tube whereby to allow the sleeve to be axially removed from the armor tube without disconnecting said wires.

3. A lighting unit for a display case or the like comprising an electrical supply socket adapted

to be fixedly mounted in the case, a positioning plate adapted to be fixedly mounted in the case opposite the socket, a transparent armor tube adapted to be disposed axially between the socket and plate, the armor tube being shorter

5 than the distance between said socket and plate and having a longitudinally disposed guide slot extending through its top end from a point adjacent said end, a sleeve telescopically mounted 10 on the upper end of the tube, an electrical connector carried on the top end of the sleeve for locking engagement in said socket, a pair of light 15 sockets slidably mounted in the armor tube, an elongated electrical lighting tube disposed longitudinally in said armor tube between said light 20 sockets, wires leading from the connector to the light sockets, there being an excess length of said wires between the connector and light sockets whereby to allow the sleeve to be axially removed from the armor tube without disconnecting said wires, and a radial projection on the top light socket slidably fitting in said guide slot.

4. In a display cabinet having a top wall, a 25 bottom wall, side walls and a doorway in one of the side walls, an electrical socket member fixedly carried by the top wall adjacent the doorway, a cup-shaped positioning member secured to the floor directly under the socket

30 member, a transparent armor tube having its bottom end fitted in the positioning member and having its open top end terminating short of the socket member, a sleeve telescopically mounted on the top end of the armor tube, an electrical connector carried by the sleeve for locking engagement with the socket member, a lighting element removably mounted in the armor tube comprising a fluorescent tube light, end sockets for the latter tube, disks carrying the respective 40 end sockets, a substantially rigid tube connected to and holding the disks in spaced relation to each other longitudinally of the armor tube, and wires connecting the end sockets to the connector.

45 5. In a display cabinet having a top wall, a bottom wall, side walls and a doorway in one of the side walls, an electrical socket member fixedly carried by the top wall adjacent the doorway, a cup-shaped positioning member secured to the floor directly under the socket

50 member, a transparent armor tube having its bottom end fitted in the positioning member and having its open top end terminating short of the socket member, a sleeve telescopically mounted on the top end of the armor tube, an electrical connector carried by the sleeve for locking engagement with the socket member, a lighting element removably mounted in the armor tube comprising a fluorescent tube light, end sockets

55 for the latter tube, disks carrying the respective end sockets, a substantially rigid tube connected to and holding the disks in spaced relation to each other longitudinally of the armor tube, and wires connecting the end sockets to the connector.

60 65 6. The device of claim 4 wherein the outer portion of the armor tube towards the doorway is coated with a light reflective material, wherein the upper end of the armor tube is longitudinally slotted and wherein the upper disk has a radial projection slidably fitting in said slot

70 75 whereby to retain the lighting element in posi-

tion with the substantially rigid tube disposed between the lighting tube and said outer portion of the armor tube.
